MULTIPLE-CYLINDER COMPRESSION PUMP.

1,413,933.

Specification of Letters Patent. Patented Apr. 25, 1922.

Application filed February 21, 1920. Serial No. 360,391.

To all whom it may concern:

Be it known that I, JOHN R. PRICE, a citizen of the United States, residing in Charlottesville, in the county of Albemarle and State of Virginia, have invented certain new and useful Improvements in Multiple-Cylinder Compression Pumps, of which the following is a specification.

My present invention relates to an improvement in multiple cylinder compression pumps, the pump being operated by the explosive cycle of a multiple cylinder internal combustion engine, such for instance, as the well-known automobile type.

One advantage of my pump is that it is entirely automatic, simple as to its parts, efficient in service, easy to assemble and disassemble, and capable of withstanding hard use.

Another advantage is that it may be used on internal combustion engines having a large or small bore and stroke, and it will operate as efficiently on a small-bore small-stroke low power engine, as on a so-called long-stroke high-pressure type, and without any adjustment whatever of either the engine or my pump.

A particular feature of my invention is the use of adjacent cylinders having space for communication between the cylinder interiors, and each cylinder having a plunger therein, and means appurtenant to said space and operatively connected to the plungers for providing concurrent movement of the plungers by movement of either one of the plungers.

In the present embodiment of my invention this concurrent movement is produced by racks operatively connected to the plungers, a rack for each plunger, and a pinion coacting with the racks.

Other features and advantages of my invention will be disclosed in the course of the description of my invention.

In the drawings forming part of this specification,

Figure 1. is a plan view of my pump connected to a multiple cylinder engine and connected to an air tank.

Fig. 2, is a front elevation of my pump. 50
Fig. 3, is a sectional view on the line 3—3 of Fig. 2.

Fig. 4, is a sectional view on the line 4—4 of Fig. 3, two of the piston or plunger heads being shown in full, and one partly broken 55 away, and one in section, and the lower or valve end of my pump being shown in section on the line x—x of Fig. 5, next below mentioned.

Figure 5, is a bottom plan view of the 60 cage comprising the air intake and outlet valves of my pump.

Figure 6, is a plan view of the valve protecting stop plate or cover.

Similar reference characters denote similar parts throughout the several views.

My invention comprises in its main parts or elements the twin cylinders A A, each having therein a piston or plunger generally denoted by B, each piston or plunger 70 being provided with a pressure piston-head C and an air compression piston-head D, having between the respective piston-heads a rack E; the pinion F located in the cylinder partitioning wall and coacting with or 75 engaging each of the racks E; and the cage G comprising the air intake valves and air outlet valves.

The cylinders A A are shown connected to a multiple cylinder internal combustion engine generally denoted by M, either two or four cycle, and preferably a four cylinder four cycle engine.

The cylinders A are provided with a casting 10 having a partitioning wall 11 between 85 the cylinders with space therein to receive the pinion F. The cover cap 12 for the cylinders A is removably secured to the cylinders in any suitable manner, as by the bolts 13. The cover cap 12 has therein threaded, 90 or otherwise suitably arranged, apertures or holes 14 and 14^a, an aperture for each cylinder, for attaching means, such as the ducts 14^b and 14^c, for connecting the pump cylinders to the engine cylinders, whereby explosion pressure is permitted to enter the actuation chambers or spaces of the pump cylinders.

Each of the pistons or plungers B comprises the bolt, generally denoted by 15, provided with the removable head or nut 16, the stem 17, the bottom or stop plate 18, the pressure piston-head C, and air compression piston-head D.

Each pressure piston-head C preferably consists of three disks, shown in Fig. 4, that is, two upper disks 19, and an under disk 20. The disks 19 and the disk 20 are alike in having an aperture therethrough for receiving the stem 17 of the bolt 15, but the disks 19 are each provided with an annular recess 21 for piston rings, while the disk 20 is provided with an annular recess 22 for receiving a lubricating means or swab, which rings and lubricating means are later described.

Each of the air compression piston-heads D preferably consists of two disks 23 and 24, an upper and an under disk, the disks 23 and 24 each having an aperture therethrough for receiving the stem 17 of the bolt 15. The disk 23 has an annular recess 25 for receiving a lubricating means or swab, while the under disk 24 is provided with annular recesses 26 for receiving piston rings similar to those of the disks 19, the lubricating means of the disk 23 differing from that of the disk 20 and being later described. But I do not restrict myself to pressure piston-heads or air compression piston-heads composed of separate disks, as such heads may be of one piece form arranged to receive the piston rings and lubricating means, the disk construction, however, being preferable as facilitating the manufacture and assembling of my device.

Each rack E is a cylindrical member, in cross-section, provided on its exterior with convolutions or annular teeth 27, and provided with a central bore to receive the stem 17 of the bolt 15.

The pinion F is located in the partition wall 11, in an opening 28 therein, and is loosely mounted on a shaft or bolt 29, which passes through the cover or plate 30 removably bolted or suitably attached to the pump cylinder front walls, the shaft 29 then passing through the pump cylinder front wall substantially in the line of the partition wall and across the opening 28 thereof and into the pump cylinder rear wall. The pinion F is held in place by the stop collar 31, of the shaft 29, and by the bushing 32 which occupies a space 33 provided in the pump cylinder front wall and partition wall, the bushing being of suitable fibre or any suitable bearing metal, the space 33 occupied by the bushing 32 being of sufficient size to permit insertion or removal therethrough of the pinion F and stop collar 31, and the cover or plate 30, having a hole therethrough for the shaft 29, also providing a cover for the bushing. The pinion F is arranged on

the shaft 29 to coact with or engage adjacent racks E when the parts are in operative relation, the teeth of the pinion engaging the convolutions or teeth 27 of each rack. The use of convolutions or annular teeth, such as 27, in cooperation with a pinion such as F, permits rotation of the plungers B in the cylinders in operation, tending to preserve the interior of the cylinders.

The valve cage G is provided with air intake valves 34, preferably two air intake valves for each pump cylinder, these valves being of the usual construction and spring-actuated in a known manner, and intended to admit air into the compression chamber or space of the pump cylinders. The valve cage G is provided with exhaust valves 35, preferably one exhaust valve for each pump cylinder, each exhaust valve 35 opening to a duct 36, which ducts 36 of the exhaust valves open to a common exhaust outlet 37 arranged for connection to a pipe or conduit 38, or other suitable means, for conveying compressed air from either of the pump cylinders to a receiver such as the tank 39, Fig. 1. The cover plate 40, Fig. 6, is provided to hold the coacting valve-operating springs 41 in operative position, and preferably is provided with four groups of air inlet openings 42, a group for each air intake valve 34, to protect the air intake valves. The cover plate 40 and the valve cage G are secured to the bottom of the pump cylinders by any suitable removable means, such as the bolts 43.

In assembling my device: Each piston or plunger B is first assembled outside of its cylinder A. The head of nut 16 of the bolt 15 is removed and an under disk 24 of the compression piston-head D is passed over the stem 17 and down against the stop plate 18, the rings 44, which are of the split-ring type, being first located in the recesses 26 by pressing them upwardly and downwardly, as the case may be, into the recesses 26, thus avoiding all danger of breaking the rings, as would arise were it necessary to spring the rings over the greatest diameter of the disk and then locate the rings in recesses, as is customary, an advantage of my disk construction of the piston-heads thus being obvious.

The upper disk 23 is passed over the stem 17 and down against the under disk 24, the lubricating means or swab 45 being first located in the recess 25.

The lubricating means or swab 45 is preferably of fibrous material, or any material adapted to retain and distribute oil in a swabbing manner on the pump cylinder interior wall. The rack E is passed over the stem 17 and down against the disk 23. An under disk 20 of the pressure piston head C is passed over the stem 17 and down against

the rack E, the lubricating means or swab 46 being first located in the recess 25, the lubricating means in this case being a heat-resisting, flexible metal or material, such as 5 brass tinsel, adapted to retain and distribute oil in a swabbing manner on the pump cylinder interior wall.

The upper disks 19 of the pressure piston-head C are then passed over the stem 17, 10 for convenience in construction, and down against the upper end of the rack E, the piston rings 44 being first located in the recesses 21. The head or nut 16 is screwed down upon the stem 17 upon the parts and an 15 assembled piston or plunger is provided. A further advantage of the pressure piston-head and air compression piston-head composed of disks is obvious from the above description of assembling.

20 A piston or plunger B thus assembled is inserted in each of the pump cylinders A, either from the bottom of the cylinders, the valve cage G and bottom plate 40 not yet being in place and the top cover plate 12 25 being in place, or, if more convenient, the piston or plunger B may be inserted from the top of the pump cylinders, the valve cage G and bottom plate 40 being in place, and the top cover plate 12 not being in place, 30 and the valve cage and bottom plate, or the top cover plate, as the case may be, is then secured to the pump cylinders. To insert the pinion F and its supporting parts into the pump cylinders, the journal bolt or shaft 35 29 of the pinion is passed through the opening 33 for the bushing 32, and across the opening 28 in the partition wall 11 and seated in the pump cylinder rear wall in a suitable recess therefor. The stop collar 31 40 is passed with the shaft 29 inwardly and against the pump cylinder rear interior wall, the opening in the partition wall permitting this, the pinion F is passed over the shaft 29 and inwardly against the stop collar, the 45 bushing 32 is passed over the shaft 29 and into contact with the pinion F, and the cover or plate 30 is secured over the end of the shaft 29 and to the pump cylinder front exteriors.

50 Oil may be introduced into the pump cylinders by removal of the cover or plate 30 and bushing 32, or suitable plugs, not shown, may be provided in the pump cylinder walls for introducing oil, the oil when introduced 55 into the pump cylinder interiors being distributed by the reciprocal movement of the racks E and rotation of the pinion F.

In operation: Assuming that the firing order of the four cylinders of the engine, 60 Fig. 1, may be either of the 1-3-4-2, or that it may be of the 1-2-4-3 order, it is desirable, as found in practice, to tap the intermediate cylinders K and L of the engine with duct members such as 14^b and 65 14^c which are connected to respective pump

cylinders. If explosion occurs during the normal running of the gas engine or motor in cylinder K, then that piston or plunger, of the pump cylinder connected to the duct 14^b from the cylinder K is forced downwardly about as shown in Fig. 4, and the air originally in the air compression chamber or space of such pump cylinder is expelled through the duct leading to the air tank. It is obvious that if the engine, Fig. 75 1, is running on the 1-3-4-2 sequence of explosion, the cylinders K and L will never fire together, but will fire alternately, and cylinder K will fire and cylinder L will 80 siphon simultaneously and in the next position the reverse of this will be true. The foregoing also applies to engines running on the 1-4-3-2 sequence, and that even in this sequence the cylinders K and L will fire alternately. When this alternate firing occurs, the high pressure generated in that cylinder K or L which is in connection with its respective pressure chamber or space of the pump cylinder will cause the respective plunger or piston of the pump to operate 85 downwardly by reason of such explosion transmitted through the ducts 14^b or 14^c, as the case may be, and that alternate explosions in the cylinders K and L will 90 alternately operate to cause one piston or 95 plunger of the pump to move downwardly and the opposite piston or plunger to move upwardly through the action of the pinion F and racks E. It will thus be seen that the alternate high pressures in the cylinders 100 K and L will operate the pistons B for an air compression stroke, and that the air thus compressed will be forced into the air tank until a sufficient volume and pressure has 105 been introduced.

Should either of the cylinders K and L misfire, or should there be a weak explosive mixture, the respective pistons or plungers B will operate to the extent of the power introduced thereto, and no harm can be done 110 to the pump by any lack of cycle or increase of explosive pressure transmitted.

Having thus described my invention, it should be understood that there may be modifications thereof and variations therein 115 without departing from the spirit of the invention or exceeding the scope of the appended claims.

Having thus described my invention, I 120 claim:

1. A pressure actuated pump comprising cylinders, means for connecting the cylinders to each other having space therein providing communication between the cylinder interiors, a plunger in each cylinder movable in 125 one direction by direct pressure and free from reciprocation by direct pressure in the opposite direction, and means operatively occupying said space and coacting with the plungers for providing, when either of the 130

plungers is moved by direct pressure, concurrent movement of the other plunger to position for movement by direct pressure.

2. A pressure actuated pump comprising 5 adjoining cylinders, means for connecting the cylinders to each other having space therein providing communication between the cylinder interiors, a plunger in each cylinder movable in one direction by direct 10 pressure and free from reciprocation by direct pressure in the opposite direction, and means operatively occupying said space and coacting with the plungers for providing, when either of the plungers is moved by direct pressure, concurrent movement of the other plunger to position for movement by direct pressure.

3. A pressure actuated pump comprising 20 adjoining cylinders arranged parallel to each other, means for connecting the cylinders to each other having space therein providing communication between the cylinder interiors, a plunger in each cylinder movable in one direction by direct pressure and free 25 from reciprocation by direct pressure in the opposite direction, and means operatively occupying said space and coacting with the plungers for providing, when either of the plungers is moved by direct pressure, concurrent movement of the other plunger in 30 direction opposite to the movement of the first plunger to position for movement by direct pressure.

4. A pressure actuated pump comprising 35 cylinders, means for connecting the cylinders to each other having space therein providing communication between the cylinder interiors, a plunger in each cylinder having a rack portion, the plunger being movable in 40 one direction by direct pressure and free from reciprocation by direct pressure in the opposite direction, and a pinion operatively occupying said space and engaging the rack portions of the plungers for providing, when 45 either plunger is moved by direct pressure, concurrent movement of the other plunger to position for movement by direct pressure.

5. A pressure actuated pump comprising 50 cylinders, means for connecting the cylinders to each other having space therein providing communication between the cylinder interiors, a floating plunger in each cylinder provided with a rack portion having annular teeth, the plunger being movable in one 55 direction by direct pressure and free from reciprocation by direct pressure in the opposite direction, and a pinion operatively occupying said space and engaging the annular teeth of the rack portions of the plungers 60 for providing, when either of the plungers is moved by direct pressure, concurrent movement of the other plunger to position for movement by direct pressure.

6. A pressure actuated pump comprising 65 cylinders, means for connecting the cylinders

to each other having space therein providing communication between the cylinder interiors, a plunger in each cylinder movable in one direction by direct pressure and free from reciprocation by direct pressure in the opposite direction, means operatively occupying said space and coacting with the plungers for providing, when either of the plungers is moved by direct pressure, concurrent movement of the other plunger to position for movement by direct pressure, and means for exerting initial direct pressure on either of the plungers and subsequently exerting direct pressure on each of the plungers alternately.

7. A pressure actuated pump comprising cylinders, each cylinder having an actuation end and a pump end, means for connecting the cylinders to each other having space therein providing communication between the cylinder interiors; a plunger in each cylinder provided with an actuation head and a pump head, the plunger being movable in one direction by direct pressure on the actuation head and being free from reciprocation by direct pressure in the opposite direction on the pump head, means operatively occupying said space and coacting with the plungers for providing when either of the plungers is moved by direct pressure, concurrent movement of the other plunger to position for movement by direct pressure, and means for exerting initial direct pressure on the actuation head of either of the plungers and subsequently exerting direct pressure on the actuation head of each plunger alternately.

8. A pressure actuated pump comprising, with means for supplying pressure, adjoining cylinders, means for connecting the cylinders to each other having space therein providing communication between the cylinder interiors, means for connecting the cylinder interiors to said pressure supplying means, a plunger in each cylinder movable in one direction by direct pressure from said pressure supplying means and free from reciprocation by direct pressure in the opposite direction, and means operatively occupying said space and coacting with the plungers for providing, when either of the plungers is moved by direct pressure from said pressure supplying means, concurrent movement of the other plunger to position for movement by direct pressure from said means.

9. A pressure actuated pump comprising adjoining cylinders, means for connecting the cylinders to each other having space therein providing communication between the cylinder interiors, a plunger in each cylinder movable in one direction by direct pressure and free from reciprocation by direct pressure in the opposite direction, means operatively occupying said space and

coacting with the plungers for providing, when either of the plungers is moved by direct pressure, concurrent movement of the other plunger to position for movement by direct pressure, and means for introducing lubricant into one cylinder, the lubricant being introduced from said cylinder into the adjoining cylinder through said communicating space.

- 10 10. A pressure actuated pump comprising, adjoining cylinders, means for connecting the cylinders to each other having space therein providing communication between the cylinder interiors, a plunger in each cylinder movable in one direction by direct pressure and free from reciprocation by direct pressure in the opposite direction, means operatively occupying said space and coacting with the plungers for providing, 15 when either of the plungers is moved by direct pressure, concurrent movement of the other plunger to position for movement by direct pressure, and means for introducing lubricant into one cylinder, the lubricant being introduced from said cylinder into the adjoining cylinder through said communicating space and being distributed by said coacting means and by the plungers.

11. A pressure producing pump having 30 adjoining cylinders and adapted to be brought into fluid pressure actuating connection with a fluid pressure engine; means for separating the pump cylinder interiors having space therein for communication between the cylinder interiors; means for introducing lubricant into the cylinders; a double-headed plunger piston for each cylinder, having an annular rack-gear between the two piston heads of each cylinder; an idler gear-wheel in the space communicating with the two cylinders and coacting with the rack-gear of both plungers, for providing concurrent movement of the plunger pistons by movement of either one of such pistons; and means for alternately moving the plungers, said plungers and said coacting means providing means for distributing lubricant for the cylinders and mechanism.

12. A pressure producing pump having 50 adjoining cylinders, means for separating the cylinder interiors having space therein for communication between the cylinder interiors; a plunger in each cylinder provided with an upper and a lower piston-head; means for introducing lubricant into each cylinder between said piston-heads; means operatively occupying said space and coacting with the plungers for providing concurrent movement of the plungers by movement of either one of the plungers; and means for moving the plungers; said plungers and said coacting means providing means for distribution of the lubricant.

13. In a pressure producing pump, in combination, adjoining cylinders; means for

separating the cylinder interiors having space therein for communication between the cylinder interiors; a plunger in each cylinder having rack means appurtenant thereto; a pinion occupying said space and engaging said rack means for providing concurrent movement of the plungers by movement of either one of the plungers; a shaft for said pinion, the cylinders having an opening therein for introduction of said pinion and shaft into said space and for providing means for introducing lubricant into the cylinders; means for securing the inner end of said shaft to the cylinders; a removable bushing for the outer end of said shaft; a removable cover for said opening providing means for securing the outer end of said shaft; and means for moving the plungers.

14. A fluid pressure pump comprising adjoining cylinders; means for separating the cylinder interiors having a space therein for communication between the cylinder interiors; a plunger for each cylinder; means operatively occupying said space and coacting with the plungers for providing concurrent movement of the plungers by movement of either one of the plungers; and fluid pressure inlets one for each cylinder at the adjacent ends of the cylinders, whereby one cylinder may be brought into communication with one cylinder, and the other with another cylinder of an internal combustion engine or motor, which are alternately under pressure.

15. A fluid pressure pump comprising adjoining cylinders; means for separating the cylinder interiors having a space therein for communicating between the cylinder interiors; a plunger for each cylinder provided with a rack-gear having annular teeth; a pinion operatively occupying said space in mesh on one side with the annular teeth of one plunger and on the other with those of the other plunger; and fluid pressure inlets one for each cylinder at the adjacent ends of the cylinders, whereby one cylinder may be brought into communication with one motor cylinder, and the other with another motor cylinder of an internal combustion engine or motor which alternately delivers fluid individually, one to one cylinder and the other to the other cylinder.

16. A fluid pressure pump comprising adjoining cylinders; means for separating the cylinder interiors having a space therein for communicating between the cylinder interiors; a plunger for each cylinder provided with a rack-gear having annular teeth; a pinion operatively occupying said space in mesh on one side with the annular teeth of one plunger and on the other with those of the other plunger; fluid pressure free unvalved inlets, one for each cylinder at the adjacent ends of the cylinders, whereby one cylinder may be brought into

free communication with one cylinder, and the other with another cylinder of an internal combustion engine or motor, which cylinders are alternately under pressure.

5 17. A fluid pressure pump of the class described, comprising a double cylinder integrally formed casing or housing, having an opening in the central wall dividing the cylinders; a double headed piston plunger 10 reciprocatingly mounted in each cylinder, having a rack-gear between the piston-heads; and a gear-pinion revolvably carried in the opening in the central wall in mesh with the rack-gear of each of the piston 15 plungers.

18. A fluid pressure pump of the class described, comprising a double cylinder integrally formed casing or housing, having an opening in the central wall dividing the 20 cylinders; a double headed piston-plunger reciprocatingly mounted in each cylinder, having an integrally formed annular peripheral rack-gear between the piston heads; and a gear-pinion revolvably carried in the 25 opening in the central wall in mesh with the rack-gear of each of the piston-plungers; means for air intake for the compression of the air; and means for outlet of the compressed air located at the same end of the 30 two cylinders; and means at the opposite end of the cylinders for bringing the actuating piston-heads at such ends into free communication with two alternately acting sources of fluid pressure.

35 19. A fluid pressure pump of the class described, comprising a double cylinder integrally formed casing or housing, having an opening in the central wall dividing the cylinders; a double headed piston-plunger 40 reciprocatingly mounted in each cylinder, carrying a rack-gear between the piston heads; and a gear pinion revolvably carried in the opening in the central wall in mesh with the rack-gear of each of the piston 45 plungers; means for air intake for the compression of the air; and means for outlet of the compressed air located at the same end of the two cylinders; and means located at the opposite end of the cylinders for bringing 50 the actuating piston-heads at such ends into free communication with two alternately acting sources of fluid pressure.

20. A fluid pressure pump of the class described, comprising a double cylinder integrally formed casing or housing, having an opening in the central wall dividing the cylinders; a double headed piston-plunger reciprocatingly mounted in each cylinder, carrying a rack-gear between the piston- 55 heads; a gear-pinion revolvably carried in the opening of the piston-plungers; means for air intake for compression of the air; means for outlet of the compressed air; and means located at the opposite end of the 60 cylinders for bringing the actuating piston- 65

heads at such ends into free communication with two alternately acting sources of fluid pressure and exhaust.

21. In combination, adjacently relative cylinders; means for connecting the cylinders having space therein providing communication between the cylinder interiors; a floating piston-plunger in each cylinder; means operatively occupying said space and cooperating with the piston-plungers for 70 providing concurrent movement of the piston-plungers by movement of either one of the piston-plungers; and means for moving the piston-plungers; said piston-plungers and said coacting means being adapted for 75 permitting rotary movement of the piston-plungers in the cylinders.

22. In combination, adjacently related cylinders; means for connecting the cylinders having space therein providing communication between the cylinder interiors; a floating plunger in each cylinder having compression heads and a connecting stem, the stem having annular teeth thereon; a pinion operatively occupying said space and 85 engaging the annular teeth of each of the plunger stems for providing concurrent movement of the plungers by movement of either one of the plungers; and means for 90 moving the plungers.

23. In combination, adjacently related cylinders; means for connecting the cylinders having space therein providing communication between the cylinder interiors; a floating plunger in each cylinder having 100 compression heads and a connecting stem, the stem having annular teeth formed thereon; a pinion operatively occupying said space and engaging the annular teeth of each 105 of the plunger stems for providing concurrent movement of the plungers by movement of either one of the plungers; and means for moving the plungers.

24. In a pressure producing pump, in combination, adjacently related cylinders; means for connecting the cylinders having space therein providing communication between the cylinder interiors; a double headed plunger in each cylinder; means operatively occupying said space and coacting 110 with the plungers for providing concurrent movement of the plungers by movement of either one of the plungers; a cage provided with a plurality of fluid intake means for the cylinders, said intake means communicating with and being equally distributed to the cylinders; said cage being provided with means communicating with each cylinder for outlet of compressed fluid therefrom; and means for alternately moving the plungers.

25. In a pressure pump, in combination, adjacently related cylinders; means for connecting the cylinders having space therein providing communication between the cylinders.

der interiors; a double headed plunger in each cylinder; means operatively occupying said space and coacting with the plungers for providing concurrent movement of the 5 plungers by movement of either one of the plungers; a cage provided with a plurality of fluid intake valves, said intake valves communicating with and being equally distributed to the cylinders; said cage being

provided with means communicating with each cylinder for outlet of compressed fluid therefrom, said means communicating with a common outlet for compressed fluid; and means for alternately moving the plungers.
